UNITED STATES PATENT OFFICE.

JOSEF BLAHA, OF CLEVELAND, OHIO.

WALL CONSTRUCTION FOR BUILDINGS.

1,170,215.

Specification of Letters Patent.

Patented Feb. 1, 1916.

Application filed April 19, 1915. Serial No. 22,316.

To all whom it may concern:

Be it known that I, JOSEF BLAHA, a citizen of the United States of America, residing at Cleveland, in the county of Cuyahoga and 5 State of Ohio, have invented certain new and useful Improvements in Wall Construction for Buildings; and I hereby declare the following to be a full, clear, and exact description of the invention, such as will enable others skilled in the art to which it pertains to make and use the same.

This invention relates to improvements in wall-construction for buildings, and pertains more especially to an improved footing 15 for an outer wall of a building.

The primary object of this invention is to provide said footing at the outer side of said wall with a water-conducting passageway which is formed in and extends longitudinally of the upper portion of the footing and has its bottom sloping downwardly in the direction of the discharging end of said passageway, and to provide said footing at the outer side of said passageway with a seat 25 extending longitudinally of the passageway and sloping downwardly in the aforesaid direction and affording support to a cover for said passageway.

Another object is to form said footing of 30 special blocks of concrete or artificial stone, and to have each block provided in its outer side portion with a recess, extending endwise of the upper portion of the block and adapted to form a portion of the aforesaid 35 water-conducting passageway, and to have said block provided at the outer side of said recess with an upwardly facing shoulder which extends longitudinally of said recess and forms a portion of the hereinbefore 40 mentioned seat for the aforesaid cover.

With these objects in view, and to the end of attaining any other advantage hereinafter appearing, this invention consists in the improved footing hereinafter described, and 45 in the hereinbefore mentioned special block adapted to form a portion of said footing.

In the accompanying drawings, Figure 1 is an outer side view of a portion of an outer wall of a building, and portions are 50 broken away and in section in this figure to more clearly show the construction. Fig. 2 is a vertical section on line 2—2, Fig. 1. Fig. 3 is a top plan of a special concrete block employed in forming the footing of 55 said wall. Fig. 4 is an outer side view of

said block. Fig. 5 is a right-hand-end elevation relative to Fig. 4.

Referring to Figs. 1 and 2 of said drawings, A indicates an outer wall of a building; a represents concrete blocks forming the footing of said wall, and B indicates the earth on which said footing rests. The blocks a are arranged longitudinally of the footing and in line endwise, and each block is provided in its outer side portion and at 60 the outer side of the wall with a recess 10 arranged at the top and extending endwise of the upper portion of the block and adapted to form a portion of a water-conducting passageway with which the footing is provided at the outer side of the wall. The recess 10 in each block, except in the end block shown, extends endwise through the block, and the recess in said end block communicates through a hole 12 formed in the 65 block with a drain-pipe D. Each block is provided at the outer side of its recess 10 with a shoulder 13 which extends longitudinally and from end to end of said recess, and said shoulder and the bottom of said 70 recess slope downwardly correspondingly in the direction of the discharging end of the passageway of which said recess forms a portion.

My improved footing-block is shown detached in Figs. 3, 4, and 5.

It will be observed that my improved footing-block forms a portion of the footing of the wall illustrated in Figs. 1 and 2, that said footing is provided at the outer side of 90 the wall with a water-conducting passageway which is formed in and extends longitudinally of the upper portion of the footing and is formed by the recesses 10 in the blocks composing said footing, that said 95 footing is provided at the outer side of said passageway with a seat extending longitudinally of the passageway and formed by the shoulders 13 of said blocks, and that said seat and the bottom of said passageway slope 100 downwardly correspondingly in the direction of the discharging end of the passageway. A cover is provided for said passageway and is preferably composed of slabs E of concrete or artificial stone, which slabs 105 extend across and longitudinally of said passageway as shown in Figs. 1 and 2. The slabs E are seated on the seat formed by the shoulders 13 of the footing-blocks and extend from said seat to and just lean against 110

the outer side of the wall at a point above the footing of the wall, and said side of said wall and the inner side wall of the aforesaid passageway are flush where the first-mentioned wall extends upwardly from said footing, as shown in Fig. 2, and obviously any water running down said side of said first mentioned wall from above the cover-slabs E and between said slabs and said side 10 of said first wall is received and conducted off by said passageway, and consequently there is little liability of any of the water received by said passageway escaping inwardly across the tops of the footing-blocks 15 to the inner side of the wall A. Not unimportant also is the leaning of the cover-forming slabs against the outer side of the wall A at a point spaced upwardly from the tops of the inner portions of the footing-blocks, as 20 shown in Figs. 1 and 2, so that water can not creep laterally onto said tops from any ground or material (not shown) at the outer sides of said slabs. By my improved construction and relative arrangement of the 25 parts all water drained to the aforesaid passageway must pass vertically downwardly at the upper edges of said slabs into

said passageway or laterally into said passageway at the shoulders 13 of said slabs.

What I claim is:—

In an outer wall of a building, a footing provided at the outer side of the wall with a water-conducting passageway which is formed in and extends longitudinally of the upper portion of the footing, said footing being provided at the outer side of said passageway with a seat extending longitudinally of the passageway, and a cover for said passageway, which cover is formed of slabs which are seated on the aforesaid seat and curved outwardly in cross-section and lean against the wall at a point above the footing, the outer side of said wall and the inner side wall of the aforesaid passageway being flush where the first-mentioned wall extends upwardly from the footing.

In testimony whereof, I sign the foregoing specification, in the presence of two witnesses.

JOSEF BLAHA.
